OPERATING TABLE

The present invention relates to a surgical operating table in which the actuating elements for the adjusting mechanisms are arranged on a pivotal arm the pivot axis of which is located approximately perpendicular with regard to the patient-supporting plane.

Modern surgery requires that the operating table, in addition to permitting an advantageous placing of the patient in different positions without impeding the movements of the surgeon, also permits an unimpeded intraoperative X-ray possibility for the obtainment of X-ray photographs as well as for the fluoroscopy with X-ray picture amplifying devices. Finally, it is required that the operating table can be actuated from one central positions which will not interfere with the action of the operating team.

While these requirements can relatively easily be met with operating tables which are adjustable purely by means of electric motors, considerable difficulties are encountered when the adjustments are made manually or when motor-actuated adjusting means are employed together with mechanical transmission means. These difficulties are due already to the fact that the adjusting and actuating means are limited to a certain location.

Some heretofore known operating tables have a transmission chassis with handwheel and cranks which are operable from the head end of the table and which extend to the head end of the supporting surface of the table. This chassis which has proved very advantageous for the stability of the table and for the mounting of the transmission and the drive therefor interferes, however, with the X-ray operation so as to make the same practically impossible in the area of said chassis.

Therefore, operating tables have been developed in which the transmission chassis is limited to the longitudinal extension of the central portion of the table or is placed into the lateral portions of the table. However, in order to take the actuating elements out of the central portion of the table where they interfere with most types of operations, arms are required which either only at one table side or on both table sides, as a rule, lead to the head end. As a result thereof, an area within the thorax range is created which can be X-rayed, but frequently complications occur in connection with the manipulation of the X-ray apparatus. When arranging the arms below the patient-supporting surface, it was necessary to compromise with undesired limitations concerning the adjustability of the back-supporting portion of the table, whereas the arrangement of the arms outside the patient-supporting area interferes with the action of the surgeon.

Furthermore, operating tables have become known, in which the actuating elements for the adjusting devices are connected directly to the end of the backplate of the table. This arrangement which is favorable as to accessibility and X-ray operation but is complicated inasmuch as some joints have to be bridged. Moreover, this arrangement has the drawback that the adjusting devices can, in certain positions of the table, hardly be actuated.

All of the heretofore-known arrangements have the additional drawback that they are limited to a certain location which interferes with the universal employment of such operating tables.

With the generally desired and advantageous arrangement of the actuating elements at the head end of the table, the actuation is, in connection with all operations on the head and neck (for instance in neurosurgery, in the neck, nose and ear surgery, and with the rather frequent struma operation, etc.), not impossible but rather difficult and always there exists the danger of asepsis.

It is, therefore, an object of the present invention to provide an operating table which will overcome the above-mentioned drawbacks.

It is another object of this invention to provide an operating table which is relatively simple and inexpensive and will assure a universal use thereof.

These and other objects and advantages of the invention will appear more clearly from the following specification in connection with the accompanying drawings, in which:

FIG. 1 diagrammatically illustrates a view of a conventional movable operating table comprising the features of the present invention.

FIG. 2 is a top view of FIG. 1.

FIG. 3 diagrammatically illustrates a view of a stationary motor-driven operating table according to the invention.

FIG. 4 is a top view of FIG. 3.

FIG. 5 is a section along the line *b-b* of FIG. 11 and shows and shows the driving mechanism for a manually operable operation table.

FIG. 6 is a section along the line *c-c* of FIG. 11 and shows a portion of the drive for inclining the table about the axis *B-B*.

FIG. 7 is a section along the line *d-d* of FIG. 5 and shows the coupling mechanism of the central drive.

FIG. 8 is a view in the direction of the arrow *e* in FIG. 5 and shows the operating knob on the tilting arm.

FIG. 9 represents a section taken along the line *f-f* of FIG. 11 and shows a portion of a drive for pivoting the table about the axis *C-C*.

FIG. 10 is a section along the line *g-g* of FIG. 11 and shows the transmitting means for adjusting the portions making up the patient-supporting part of the operating table.

FIG. 11 is a section along the line *a-a* of FIG. 5 and shows the drive mechanism of a manually operable operating table.

The operating table according to the present invention, which comprises a movable or stationary foot section and an upper portion adjustable as to height, is characterized primarily in that the actuating elements for at least some adjusting devices are arranged on a pivotal arm pertaining to the upper portion, the pivot axis of said pivotal arm being approximately vertical when the patient-supporting surface of the table occupies its horizontal basic position.

Referring now to the drawings in detail and FIGS. 1 and 2 thereof in particular, the operating table shown therein comprises a supporting or foot section 1 and an upper portion 2. Connected to the upper portion 2 is an arm 3 which is tiltable about a shaft *A*. The range over which the arm 3 can be pivoted is indicated by the arc *B* and *B'* and the respective end positions are indicated in FIG. 2 by dot-dash lines. The upper portion 2 of the operating table is adapted to be adjusted as to height by means of corresponding adjusting devices known per se which are usually located within the foot or supporting section 1 and which may be of any standard hydraulic or pneumatic type.

According to FIGS. 1 and 2, the upper portion 2 of the operating table comprises a central portion 11 which at the same time may serve as transmission chassis and which carries or forms the seat plate. Furthermore, the upper portion of the operating table comprises the backplate 12 and the leg plate 13. The central portion 11 is, in a manner known per se and therefore not illustrated, together with the plates 12 and 13 which are linked thereto adapted to be inclined about a horizontal longitudinal axis of the operating table and about a horizontal transverse axis of the operating table. In addition thereto, the plates 12 and 13 may be adjusted relative to the central portion 11 and relative to each other. If the operating table has further subdivisions, also such subdivisions may be adjustable relative to each other.

As far as these adjustments are effected over adjusting transmissions or during the operation, the actuating means are mounted on the pivotal arm 3. These adjusting means, according to the particular example shown, comprise a hand-crank 31 and a selector lever 32. By means of the selector lever 32, through the intervention of suitable control shafts and linkage means, the intended transmission for the desired adjustment is controlled whereupon, by means of the central handcrank 31, the adjustment of the operating table is effected. Instead of the transmission control, also a plurality of handcranks or handwheels may be provided which through individual drive shafts, if desired through hollow shafts, actuate the various adjusting transmissions. If desired, also a plurality

of handwheels may be combined with corresponding control means and also the number of the adjusting transmissions may be selected in conformity with the particular purpose for which the table is intended. The control transmissions may also include means for adjusting the height of the operating table. Instead of providing a handcrank 31, also a motor drive may be selected.

If the shaft A, which in the basic position of the operating table is vertical, is so connected to the table that it does not follow the adjustments of said table, the arm 3 will always remain in the selected position and has to be pivoted about the shaft A only when X-rays are taken or during fluoroscopic observations or during operations in the head area. For fixing the arm 3 in the desired pivotal position, corresponding locking means may be provided which, if desired, may be operable from the free end of the arm.

If, in conformity with the illustrated embodiment, the pivotal arm 3 is so connected to the transmission chassis 11 that it follows the adjustment of said chassis, it may occur that the actuating elements 31, 32, for instance with great inclinations toward the foot or head end, can be actuated only under difficulties which is always the case when the arm is not pivotable. In such an instance, a lateral pivoting will suffice in order to bring about or restore a favorable operating position. Similarly, when the lowering or downward tilting of the backplate 12 is impeded by arm 3, it is possible to move the arm out of the way.

Referring now to FIGS. 3 and 4, these figures illustrate an operating table according to which by a unilateral protrusion of the patient-supporting surface a highly satisfactory possibility is realized for X-raying the thorax and pelvis area. The patient-supporting parts are in this instance supported by a column head 21 in which a crosshead 22 is journaled for pivoting about the shaft or axis B. The crosshead 22 supports the jaws 23 and 23' for pivoting about the axis or shaft C. The jaws 23 and 23' in their turn form the supports for the central portion (seat plate) 24 of the operating table. Pivotally connected to said central portion 24 are the lower backplate 25 and the upper backplate 26 pivotally connected to the backplate 25. In the other direction, there are pivotally arranged the right-hand and left-hand leg plates 27, 27' and 28, 28' which can be exchanged for the backplates 25 and 26.

According to the embodiment illustrated in FIGS. 3 and 4, the pivotable arms 3, 3' are respectively connected to the jaws 23, 23'. With a twin arrangement as shown in the drawing, each of the arms 3, 3' is pivotable by 180° through the arc B, B' which is of importance when, for instance during operations on the rectum or during gynecological operations, the backplates 25, 26 are exchanged for the leg plates 27, 27' and 28, 28'.

Inasmuch as the embodiment of FIGS. 3 and 4 represents an operating table with motoric adjustments, the free end of the arms 3, 3' are not equipped with a manually operable crank but have pushbuttons 33 for the turning on and turning off of the motor. Also in this instance the arms 3, 3' are provided with the transmission selector 32 for preselecting the desired adjustment. If each adjusting transmission has its own drive motor, the selector 32 is not required and may be replaced by pushbuttons or other electric switches, or the selector may be designed for electrically controlling the adjusting transmission.

FIGS. 5-11 illustrate by way of example, a manually operable operating table adapted to be operated by a centrally located crank 31. The arrangement also comprises a tiltable arm located on the longitudinal axis of the table and moving only with the adjustment as to the height and the transverse inclination of the table about the axis B-B. The table upper portion 2 is by means of screws 101 connected to the foot portion 1. The said table upper portion 2 comprises a column head 21 having a crosshead 22 pivotally journaled for pivoting about the axis B-B. Mounted in the crosshead 22 on the right and left side are jaws 23 and 23' which carry the central portion 24 (FIG. 3) of the operating table for supporting the patient.

Pivotedly mounted in the crosshead 22 is the head 301 of the tiltable driving arm 3, said head 301 being held in axial direction by means of a ring 302 which engages a groove of the head 301. The ring 302 is connected to the crosshead 22 by means of screws 303.

In the operating head 304 of the arm 3 there are journaled the hollow driving shaft 305 and the hollow coupling shaft 306. Connected to the shaft 305 is the manually operable crank 31, while the control member 32 is frictionally connected to the shaft 306.

By means of key and groove 309 and 311, the hollow shafts 305 and 306 are telescopically connected to the shafts 308 and 310 for reducing the length of the arm 3. This connection is a power connection.

15 The shaft 308 and 310 are journaled in the head 301. Mounted on shaft 308 is a bevel gear 312 which meshes with the bevel gear 313 in the head 301. Connected to shaft 310 is a fork-shaped coupling lever 314 which by means of pins 315 engages the grooves of a coupling sleeve 316 which, in its turn, is connected to the end of a bolt 317. In said bolt 317 there are pull-wedge members 318, 319, and 320, resiliently journaled on pivots 321, 322, and 323 in such a way that their engaging portion is, by means of the thrust of springs, pressed outwardly.

20 25 Bevel gear 313 is adapted to drive a hollow shaft 324 which is provided with slots to permit passage and movement of the pull-wedge members. Connected to hollow shaft 324 for rotation therewith are helical gears 325 and 326 and the bevel gear 327. When the crank handle 31 is rotated, depending on the member 32, by means of which the coupling lever 314 is tilted and the bolt 317 is axially displaced, the respective wedge members 318, 319, and 320 engage the transmission wheels 325, 326, 327 pertaining thereto which then are rotated by the hollow shaft 324 through the intervention of the bevel gear transmission 312, 313.

30 35 In the particular example shown, the control member 32 occupies its central position so that the wedge member 319 engages the groove of the helical wheel 326. The gear 326 meshes with the gear 328 which is mounted on shaft 329 journaled in the jaw 23. At the other end of shaft 329 there is located the helical wheel 330 which, in its turn, meshes with the helical wheel 331 and is connected to the shaft 332. Shaft 332 which is likewise journaled in jaw 23 has its other end provided with driving means, for instance, the bevel gear 333 which, in a manner known per se (and therefore not illustrated) conveys the rotational movement to the central supporting member 24 where, by means of suitable driving elements, the adjustment of the backplates 25, 26, or the leg plates 27, 28 is effected. When the control member 32 is adjusted upwardly up to upper abutment 307, the wedge member 320 will, in the manner described above, engage the groove of the bevel gear 327 meshing with the bevel gear 334. The bevel gear 334 is mounted on a shaft 335 in the crosshead 55 55 60 65 70 75 22 which shaft at its other end carries the worm 336. This worm 336 meshes with the worm wheel 337 which is arranged on shaft 338 in column head 21 for power transfer. At the lower end of shaft 338 there is arranged the spur gear 339 meshing with the spur gear 340 which is connected to the end of the worm 341. The worm 341 arranged in the column head 21 meshes with the worm wheel 342 which latter is threadedly connected to the bearing pivot of the crosshead 22 in a centering manner by means of screws 343. In this way, when turning the handcrank 31 the crosshead 22 is tilted about the axis B-B while the driving arm 3 which is connected to the crosshead 22 follows this tilting movement.

When the control member 32 is adjusted downwardly up to the lower abutment 307', the wedge member 318 engages the groove of the helical gear 325 which, in its turn, meshes with the helical wheel 344. On the shaft 345 journaled in the crosshead 22 are arranged on one hand the helical gear 344 and on the other hand the worm 346. Worm 346 meshes with helical wheel 347 which is connected to the driving stud of worm 348 for power transmission. The worm 348 meshes with the worm wheel 349 which is threadedly connected in a cen-

tering manner by means of screws 350 to the bearing stud of the jaw 23. It will thus be evident that when turning the handcrank 31 the jaw 23 and the part 24 are pivoted about the axis C-C.

The jaw 23' forming an additional bearing means is rigidly connected to the jaw 23 by means of the central member 24. When tilting about the axis C-C, the arm 3 does not take part in this tilting movement. It would do so only if arm 3 were, with a correspondingly changed transmission, mounted on the jaw 23 or 23' or the patient-supporting surface. In this instance, the arm 3 would tilt when a tilting action is carried out about the axis C-C and would also take part in the tilting about the axis B-B. If it were desired that the driving arm 3 carry out no tilting movements, but only adjusting movements of the table as to height, the driving arm 3 would have to be mounted on the foot part 1 with the transmission changed accordingly.

From FIG. 5 it will be obvious that the actuation of the adjusting devices by means of the handcrank 31 in any desired tilting position of the arm 3 will be possible. This is due to the fact that the tilting axis A of the head 301 coincides with the axis of the bevel gear 313. Similarly, the control of the wedge members in each tilting position is possible by means of a control member 32 because the coupling sleeve 313 is rotatably mounted on the bolt 317, the axis of which coincides with the pivot axis A of arm 3.

The arrangement of the pivot shafts A, A' is in addition to the desired pivoting range, also determined by the structural possibilities. As a rule, the arrangement in a table portion which follows entirely or partially the adjustments, greatly facilitates the structural solution.

If the arm 3 in its pivoted out position protrudes too far beyond the table, the arm may be composed of telescopic sections to permit a corresponding shortening of the arm and also a corresponding extension of the arm for special purposes.

The pivotal arm for the actuating means pertaining to the adjusting devices results in a simple manner in the following advantages:

1. Unimpeded X-raying by pivoting the arm out of the range of the X-rays.
2. Easy actuation of the actuating means by pivoting the arm to its respective most favorable actuating position.
3. Optimum working conditions for the surgeon by removing the actuating means for the adjusting devices out of the operating range.

It is to be understood that the embodiments referred to above are merely examples and that numerous modifications are possible within the scope of the appended claims.

What I claim is:

5. 1. An operating table structure which includes: supporting means, an upper portion forming the patient receiving and supporting table supported by and vertically adjustable relative to said supporting means, said table including a plurality of sections adjustable relative to each other, adjusting means 10 operatively connected to at least one of said sections for selectively adjusting the same, arm means pivotally connected to said upper portion and pivotable about a vertical axis when the top surface of said patient-supporting table is located in an approximately horizontal plane, and mechanical table-actuating 15 control means including a handcrank and a selector lever respectively mechanically operatively connected to said adjusting means and supported by said arm means.
2. A structure according to claim 1, in which the pivot axis of said arm means is the axis of a shaft positioned to determine 20 arc range in which said arm means is pivotable and moveable only in vertical direction upwardly and downwardly.
3. A structure according to claim 1, in which the pivot axis of said arm means is the axis of a shaft so mounted on the operating table structure as to change its position in conformity 25 with the inclination of at least one of said adjustable sections changeable alternately about only longitudinal, only transverse and both longitudinal and transverse axes.
4. A structure according to claim 1, in which the pivot axis of said arm means coincides with and is located approximately 30 in the longitudinal central plane of said patient supporting table.
5. A structure according to claim 1, in which said arm means comprises two arms respectively pivotally supported by said operating table structure with the pivot axes thereof 35 respectively located to the right and left on opposite sides of and substantially symmetrically to the longitudinal central plane of said patient supporting table.
6. A structure according to claim 5, in which part of the table-actuating control means is supported by one of said arms and other table-actuating control means are supported by the other one of said arms.
7. A structure according to claim 1, in which said pivotable arm means are composed of sections individually telescopically interengaging each other for selectively shortening and 40 extending said arm means.
